MEANS FOR CLAMPING FURNACES TO TORCHES

Ernest A. Starbuck, Peoria, Ill.

Application July 31, 1941, Serial No. 404,848

5 Claims. (Cl. 126—239)

This invention relates to improvements in that class of tools known as tinners' and repairmen's torches.

More particularly the invention pertains to means for attaching a furnace to the burner tube or nozzle of such torch wherein to heat soldering irons or ladles housed therein.

As is well known, there are many types of torches in use and since produced by different manufacturers they are of many forms and sizes, especially when considering the burner tubes or nozzles thereof. By reason of the many different diameters of burner tubes and the relation the tubes bear to the other parts of the torches carrying them it has been difficult to attach a furnace thereto by any single form of attaching means.

Due to the fact that a one piece clamp such as a U type of bolt, for example, is not adaptable at all times for the purpose required where a torch structure is to be considered, a two part clamp is found necessary for engaging the torch part or parts at opposite sides.

This has occasioned the two part type of clamp about to be described which has been found to be quite universal in its application.

That the invention may be fully understood I have provided the accompanying drawing forming part hereof wherein:

Figure 1 is an elevation of part of a torch showing a furnace attachment in section and my form of clamp for connecting said furnace to the burner tube of said torch;

Figure 2 is a plan of the same with parts shown broken away to better reveal structures;

Figure 3 is a transverse sectional elevation of part of the furnace structure and my clamping means produced on line 3—3 of Figure 2;

Figure 3^a is an elevation of a member as a modification of one of the members shown in the other figures of the drawing;

Figure 4 is a view similar to Figure 3 showing a burner tube or nozzle of larger diameter than that in said Figure 3, and

Figure 5 illustrates the under surface of that part of the furnace structure shown in Figures 3 and 4.

Having in view the purpose to be accomplished as stated above, the invention contemplates clamping together a burner tube and a furnace by means of two separate and independent wedgelike members, or by bolts suspended from the said furnace and free to swing at one end thereon, one at each side of said burner tube, the free end of each member abutting said tube

and also abutting a fixed part of the furnace and arranged in such manner that when said members or bolts are shifted endwise by tightening them the burner tube will be firmly clamped between them and said furnace as will appear.

In Figure 1 the character 1 denotes a portion of a torch body for containing liquid fuel surmounting which is any usual form of burner-tube 2 together with the customary needle valve 10 control-portion 3, while in both Figures 1 and 2 any usual furnace structure is illustrated to be clamped to said tube or nozzle 2. In this instance the named structure comprises a lower hollow portion 4 from which projects rearwardly on extension 5 to receive against it the said tube or nozzle, while hinged to the forward part of the portion 4 is a cover portion 6 open at its rear toward said tube, no claim of novelty being attached to the device so far described. Rather, the novelty resides in the means now to be made known. That is to say, depending from the under surface of the said extension 5 are two abutments or lugs 7 spaced from each other to receive between them the named tube or nozzle 2 as shown in the last four figures of the drawing, said nozzle extending through an opening 4' in the said lower portion, for example.

In the present instance only, these abutments or lugs are arcuate in form, at least as to channels shown therein considered in lateral section, the form of said abutments being best shown in Figure 5 viewing the same from the under side of the said extension 5, the channels of the lugs facing each other as in Figures 3 and 4, and each therefore, facing said nozzle. Spaced holes 8 in the extension 5 lie adjacent the lugs and these open into the created channels of said lugs, it being observed that the channel surfaces of said lugs are inclined at an angle downwardly and outwardly from the furnace and from each other, as in Figures 3 and 4. The surface of the channels at the free ends of the lugs, therefore, lie farther apart than do the surfaces adjacent the portion having said holes 8.

Depending from the extension 5 through each hole 8 is a threaded member 9 having a head 10, and at its threaded end being provided with a wingnut 11, for example. Quite conveniently a so-called "carriage bolt" answers the purpose in this instance the head 10 thereof being adapted to abut the named angled surface of the lug, and at the same time engage the tube or nozzle 2. The members 9 may be permitted to drop by loosening the wingnuts 11, so that they may be spread widely for entrance between them of a

tube or nozzle of practically any diameter, whereupon by drawing the members up the heads 10 will engage said tube each side thereof, whatever the diameter of said tube may be, two different sizes being shown in Figures 3 and 4 as illustrations.

Due to the fact that the inclined faces of the lugs lie closer to each other at the extension 5 as the heads 10 move upwardly the smallest or largest nozzle may be readily and firmly engaged and clamped against the under surface of the extension 5 and thus the structure 4, 5, 6 can be held rigidly with respect to the torch structure.

It is to be understood that in the present instance the rounded channels of the lugs are employed in order to accommodate the usual rounded or circular heads of the member 9, in the present case bolts, the channels guiding the heads 10, preventing the members swinging laterally. However the lugs could be otherwise formed for guide purpose while, however, retaining the angular facing surfaces to cause the members to approach each other in raising them during tightening of the wing-nuts, it being understood, of course, that the holes 8 are large enough to permit free lateral swing of the members therein.

An advantage in permitting the separate members 9 to swing relative to each is that in some makes of torch the tube or nozzle is quite close to other parts of the torch structure and cast therewith in such a position and so inclosed that a clamp of the ordinary U-bolt type cannot be used whereas the form here dealt with can firmly grip opposite sides of any structure presenting itself to which a furnace is to be attached.

Preferably the heads 10, as shown, present their more or less sharp edges to the part to be clamped so as to best serve to engage in any place of joining of the burner tube with other parts and thereby act in a secure manner.

In the drawing the heads of the bolts are shown engaging the tube 2 at the junction of the rounded tube and a depending extension of the latter. However, due to the fact that the bolts are free to swing independently it is clear that should they engage higher up or upon the rounded part of the tube, they would naturally tend to follow the curve thereof outwardly as the wing-nuts are tightened thus forcing them against the abutments or lugs, and in this way the inclined surface of a lug or the under surface of the tube will bring about the final clamping act as the head 10 is drawn up in tightening the wing-nuts.

In Figure 3^a a modification of a member or bolt is shown, the body being designated by the character 9', while 10' is the "head" thereof. This form may serve in some instance where the structure will permit, though in most cases the type shown in the other figures is adaptable to the majority of torches.

I claim:

1. The combination with the burner tube of a torch, and a furnace, of means to clamp the tube and furnace together including dual spaced abutment means fixed relatively to said furnace, the

said burner tube lying between the two, a bolt suspended at one end from the furnace at each side of said tube and free to swing, and each lying between said tube and an adjacent abutment means, and at its free end adapted to abut each of them, and means to positively shift each of the two bolts causing them to coact and to engage and clamp the tube between them and clamp the latter to said furnace.

2. The combination with the burner tube of a torch, and a furnace to be clamped thereto, of a clamp comprising two separate bolts swingingly mounted upon a part of the furnace and depending therefrom in spaced relation to each other for receiving and clamping the burner tube between them, spaced lugs carried by the furnace, the said bolts and the tube lying between said lugs with said tube abutting the furnace, and said lugs having opposed surfaces to receive the said bolts against them, said surfaces being inclined toward each other and toward that part of the furnace against which said burner tube abuts.

3. The combination with the burner tube or nozzle of a torch, and a furnace for attachment thereto, the two adapted to abut, of a pair of lugs extending from a part of the furnace and spaced from each other to receive the said tube between them and spaced from the latter, said lugs each having an inclined surface, the surfaces facing each other and lying nearest each other at their position closest to the furnace from which they extend, a member suspended at one end from the furnace at each side of the tube between the same and one of the said inclined surfaces, each member having a laterally extended portion distant from its suspended end, said portion adapted to engage the said tube, and means to impart movement to each member to cause both members to approach each other as they travel along the named inclined surfaces for engaging the said tube for and clamping together said burner and said furnace.

4. An article of manufacture consisting of a body having a cavitated portion, said body having an extension provided with a structure at one side thereof having two surfaces facing each other and spaced from each other, said surfaces lying at an angle to the plane of the extension, there being less distance between said surfaces at a position adjacent said extension than at those parts of said surfaces distant from the latter, there being an opening through the extension adjacent each of the said surfaces where they terminate at such extension, the openings being spaced apart a distance less than the distance between such surfaces.

5. The combination with the burner tube or nozzle of a torch, and a furnace adapted to be clamped with respect thereto, of a pair of spaced abutments extending from said furnace, said tube lying between said abutments in spaced relation to the same, and a wedging member lying at each side of the tube to abut the same and to engage an adjacent abutment, and means for shifting each member to wedge it between its adjacent abutment and said tube.

ERNEST A. STARBUCK.
